UNITED STATES PATENT OFFICE.

WILLIAM DE ROOY, OF NEW YORK, N. Y.

WRENCH.

1,305,887.

Specification of Letters Patent. Patented June 3, 1919.

Application filed August 27, 1918. Serial No. 251,606.

To all whom it may concern:

Be it known that I, WILLIAM DE ROOY, a subject of the Queen of the Netherlands, now residing in the city of New York, borough of Manhattan, county and State of New York, have invented a certain new and useful Wrench, of which the following is a specification.

This invention is a wrench and embodies, in combination, a monkey-wrench and a Stilson or pipe-wrench, the movable jaw of the monkey-wrench being movable to different positions, with reference to the fixed jaw of the wrench, thereby adapting it for a much wider range of work than that of the common type monkey-wrench. Moreover, the fixed jaw of the wrench is an element common to both the monkey wrench and the pipe wrench.

Features of the invention other than those specified, will be apparent from the herein-after detailed description taken in conjunction with the accompanying drawings.

In the accompanying drawings, I have illustrated one practical form of the invention, but the construction shown therein is to be understood as illustrative, only, and not as defining the limits of the invention.

Figure 1 is a side elevation of the wrench, showing the pipe jaws in closed position, and the movable jaw of the monkey-wrench so positioned as to travel at right angles to the handle of the wrench;

Fig. 2 is also a side elevation of the wrench, showing the pipe jaws in open position, and the movable jaw of the monkey-wrench so positioned as to travel in a direction in longitudinal alinement with the handle;

Fig. 3 is a side view of Fig. 2, looking in the direction of the arrow appearing on said figure;

Fig. 4 is a sectional elevation on line 4—4 of Fig. 1, looking in the direction of the arrows associated with said line;

Fig. 5 is a perspective view of the movable jaw of the monkey-wrench;

Fig. 6 is a detail view, showing the movable jaw of the monkey-wrench, when mounted as illustrated in Fig. 1, in closed position; and

Fig. 7 is a detail view, showing the movable jaw of the monkey-wrench, when mounted as illustrated in Fig. 2, in closed position.

55

Referring to the drawings, 1 designates the handle of the wrench, in one side of which is provided a groove or channel 2, preferably dove-tailed in shape, the base of which is serrated to form a rack 3. The opposite side of handle is also provided with a dove-tailed groove 4, which serves as a guide, in the manner hereinafter described.

The operating end or head of the wrench embodies a fixed jaw 5, the inner face 6 of which is plain, and comprises the fixed jaw of the monkey-wrench. The outer face 7 of fixed jaw 5 is serrated and forms the fixed jaw of the Stilson or pipe-wrench.

The head of the wrench is provided with two dove-tailed channels, 8 and 9 respectively, the former extending longitudinally of the handle, and the latter at right angles to the handle. The movable jaw 10 of the monkey-wrench, shown in perspective in Fig. 5, is so shaped at its base as to slidably fit into either channel 8 or channel 9, and, accordingly, may be mounted, with reference to the fixed jaw, either in the position as shown in Figs. 1 and 6, or the position shown in Figs. 2 and 7, thereby enabling the monkey-wrench to operate under a wide range of conditions, with reference to the location of the nuts to be manipulated.

As will be seen, more particularly from Fig. 5, the bottom of the movable jaw is provided with a rack 11, whereby it may be reciprocated in the manner to be described.

The head of the wrench is provided with an opening 12, substantially rectangular in shape, both vertically and transversely, and extending therefrom, in a direction at right angles to the axis of the handle of the wrench, is a tubular channel 13, in which a pin 14 is positioned. A worm 15 is rotatably mounted on pin 14, in co-operative relation with movable jaw 10, whereby the worm, operating in conjunction with rack 11, on movable jaw 10, serves as a means whereby said jaw may be manually reciprocated in a well known manner.

Extending on either side of opening 12 is

a second tubular channel 16, extending lengthwise of the wrench, in which pin 14 may also be positioned, with the worm 15 rotatably mounted thereon, as shown in Fig. 2, thereby positioning the axis of the worm at right angles to that which it occupies in Fig. 1, whereby it serves to reciprocate the movable jaw 10 in a direction lengthwise of the wrench.

10. In order that the pin 14 and worm 15 may be interchangeably employed in either the position shown in Figs. 1 and 6 or in the position shown in Figs. 2 and 7, the head of the pin is screw-threaded for a small portion of its length, and the end provided with the usual groove for manipulating the pin with a screw driver. The outer ends of tubular channels 13 and 16, respectively, are screw-threaded, whereby the pin 14 is securely held in place. By unscrewing the pin to a point beyond the screw-threads in the tubular channels 13 and 16, the pin may be withdrawn from one channel and inserted in the other, the worm, in the meantime, having been changed from one of its positions to the other whereupon the pin is passed through it, and thereafter locked in position.

Mounted on handle 1 is a yoke 17, the inner face of one side of which is provided with a tongue 18, which fits into groove 4 of the handle, the inner face of the other side of the yoke being also provided with a tongue 19, fitting into groove 2 of the handle. Pivotaly mounted on one side of the yoke is a dog 20, the toe of which is adapted to take into one of the serrations in rack 3, thereby enabling the yoke 17 to be locked in any desired position lengthwise of the handle. Upon releasing the dog 20 from the rack, by manually depressing the thumb-piece 21, the yoke may be moved in any desired position lengthwise of the handle.

Extending from one side of the yoke 17 are two spaced ears or lugs 22, between which is pivotally mounted a movable jaw 23, the inner face of which is serrated, as shown at 24, which serrations extend in opposite direction to serrations 7 on the outer face of fixed jaw 5, whereby the pivoted jaw 23 may coöperate with the outer face of fixed jaw 5 to perform the functions of a Stilson or pipe-wrench.

It will be noted that the wrench described is of simple construction, composed as it is of a minimum number of parts, several of which may be changed to different positions, for the purpose of enabling the wrench to be used under varying conditions of work. The wrench can be economically manufactured, and as it contains no delicate parts, is of a particularly durable construction, and, moreover, possesses pronounced efficiency for its intended purposes.

It will be understood that mechanical and formal changes may be made in the struc-

ture described, such as the substitution of equivalents, without departing from the spirit or substance of the invention, the scope of which is commensurate with the appended claims.

Having described the invention what I claim is:

1. As a new article of manufacture, a wrench embodying a handle provided at one end with a head, a fixed jaw on the head having a smooth inner face and a curved, serrated outer face, a movable jaw coöperating with the inner face of the fixed jaw, a yoke mounted for sliding movement longitudinally of the handle, a curved serrated jaw pivoted on said yoke and coöperating with the serrated face of the fixed jaw, and means coöperating with the handle and with the yoke for locking the yoke in a predetermined position longitudinally of the handle to position the pivoted jaw in adjustment relative to the curved outer face of the fixed jaw. 70

2. As a new article of manufacture, a wrench embodying a handle provided at one end with a head, a fixed jaw on the head having a smooth inner face and a curved, serrated outer face, a movable jaw coöperating with the inner face of the fixed jaw, means for mounting said movable jaw on the head so that it may travel in a path either in alignment with the axis of the handle or at right angles thereto, and a pivoted, curved, serrated jaw coöperating with the serrated face of the fixed jaw. 85

3. As a new article of manufacture, a wrench embodying a handle provided at one end with a head, a fixed jaw on the head having a smooth inner face and a curved, serrated outer face, a movable jaw coöperating with the inner face of the fixed jaw, means for mounting said movable jaw on the head so that it may travel in a path either in alignment with the axis of the handle or at right angles thereto, a pivoted, curved, serrated jaw coöperating with the serrated face of the fixed jaw, means for moving said pivoted jaw lengthwise of the handle, and means for locking it to the handle. 100

4. As a new article of manufacture, a wrench embodying a handle, provided at one end with a head, a fixed jaw on the head, having a smooth inner face and a curved, serrated outer face, a movable jaw coöperating with the inner face of the fixed jaw, a pivoted jaw having a serrated inner face coöperating with the outer face of the fixed jaw, a yoke mounted on the handle of the wrench for supporting said pivoted jaw, a rack on said handle and a dog pivoted to the yoke and adapted to be seated in the spaces between the teeth of the rack, whereby the yoke may be locked in any desired position lengthwise of the handle. 115

5. As a new article of manufacture, a wrench embodying a handle provided at one 120

end with a head, a fixed jaw on the head, two channels in said head, positioned at right angles to one another, a movable jaw provided with a rack adapted to travel in either of said channels, a worm wheel mounted on the head, and adapted to be positioned in coöperative relation to the rack, and a pin extending through the worm wheel for mounting said worm wheel for rotation while in engagement with the rack, whereby 10 the movable jaw may be reciprocated in either one of the specified channels.

In testimony whereof, I have signed my name to this specification.

WILLIAM DE ROOY.
